UNITED STATES PATENT OFFICE.

JOSEPH S. SACKETT, OF PLATTSBURG, NEW YORK.

RUFFLING ATTACHMENT FOR SEWING-MACHINES.

SPECIFICATION forming part of Letters Patent No. 257,518, dated May 9, 1882.

Application filed August 24, 1881. (Model.)

To all whom it may concern:

Be it known that I, JOSEPH S. SACKETT, a citizen of the United States of America, residing at Plattsburg, in the county of Clinton and State of New York, have invented certain new and useful Improvements in a Ruffling Attachment to Sewing-Machines; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

The object of my invention is to produce scallop-plaiting by means of a device for automatically moving the fabric to be plaited or ruffled transversely to the line of sewing, so that the fabric will be carried by the plaiter under the needle at as many different angles with the line of sewing as there are plaits in each scallop, each plait of the scallop being presented to the needle a little farther to the right or left than the one preceding, according as the direction of the fabric is affected by the operation of the moving device. I attain this object by the mechanism illustrated in the accompanying drawings, in which—

Figure 1 is a plan view of my invention complete. Figs. 2 and 3 are detail views of the same.

Similar letters of reference indicate corresponding parts.

A is the main bed-plate of the scallop attachment, designed to be connected to the bed-plate of any sewing-machine by a thumb-screw or otherwise; and it consists generally of a center, *a*, from which project the arms *b*, *c*, and *d*.

Near the extremity of the arm *b* rises a standard, *B*, on which is pivoted, at *e*, the bell-crank lever *C*, by the movement of which the scalloper is operated.

Attached to the lower end of the crank-lever *C*, and below the pivot *e*, is an arm, *f*, which is designed to engage with the reciprocating double pawl *D*, which moves back and forth horizontally on the arm *b* of the bed-plate *A*, being held in position by the crank-disk *E* and the loop on the end of the arm *b*. This pawl is divided into two arms, *g* and *h*, which act upon opposite edges of the ratchet-wheel *i*, the former being made to push against and the

latter to draw upon the teeth of the ratchet-wheel *i*, which is attached to the under side of the crank-disk *E*, which is pivoted at the center *a* of the main bed-plate *A*.

F is a slotted cross-head lying upon the upper surface of the disk, from opposite sides of which, and at right angles, project the arms *h* and *i*, which lie immediately over the arms *c* and *d* of the bed-plate *A*, and are held in place by loops at the extremities of these arms. It is operated by the adjustable crank-pin *j*, which moves in the slot as the disk revolves, thereby giving to its arms *h* and *i* an intermittent motion from right to left, and vice versa. The disk has a series of holes in it arranged at different distances from the center, and this crank-pin can be adjusted from one hole to the other, according to the length of stroke it is desired to give the arms.

The crank-pin *j* can be inserted in the disk at any desired distance from the center, for the purpose of regulating the transverse movement of the arms of the cross-head.

On the arm *h* is a movable slotted guide, *G*, which is held in position on the arm by a set-screw, *k*. For convenience in its adjustment the arm *h* can be graduated.

In operation the scalloper is first attached to the bed-plate of the machine in such a manner that the needle set-screw can be passed through the elongated slot of the crank-lever *C* and so adjusted that it shall move freely in the slot, the arms *h* and *i* being in front and lying transversely to the feed of the machine. The plaiter or ruffler, which is designed to be used in connection with the movable guide in a manner similar to that shown in my application No. 40,770, filed August 26, 1881, is then placed in its working position. The fabric to be plaited or ruffled is then placed in the guide *G* on the arm *h*. Then adjust the crank-pin *j* in the disk *E* according to the depth and shape of the scallop desired.

The farther the pivot is placed from the center of the disk the greater is the transverse movement of the bar *h* and the deeper will be the scallop.

If it is required to change the depth of the scallop and retain the same shape, then move the guide *G* to the left on the bar *h* to increase the depth and to the right to decrease it.

The perpendicular movement of the needle-

bar operates the crank-lever C, which imparts through the arm f a reciprocating motion to the double pawl D, which, acting upon the ratchet-wheel of the disk E, revolves it, thereby giving to the arms h and i of the cross-head F an intermittent motion transversely, carrying the holder G with the fabric to be scalloped to the right while one-half of the number of plaits of the scallop are being made by the plaister and to the left while the other half are being made, the number of plaits being always equal to the number of teeth in the ratchet-wheel i.

The peculiar construction and operation of the pawl D enable the operator, if he so desires, to revolve the disk E while the needle is in the fabric, as then, by the position of the crank-lever C, the pawl is drawn back, and thus allows the free revolution of the disk. When the needle is out of the fabric the pawl is carried forward by the elevated crank, and thus prevents the revolution of the disk while held in that position.

By my invention great variety can be readily given to the form and depth of the scallops

without affecting the perfect uniformity of the 25 plaisting.

What I claim, and desire to secure by Letters Patent, is—

1. The combination of the crank-lever C, the double pawl D, a ratchet-wheel, a revolving 30 wheel or disk carrying a crank-pin, and a reciprocating cross-head carrying a guide, G, substantially as shown.

2. The combination, with the crank-lever C and the double pawl D, of the guide G and 35 intermediate mechanism, substantially as described, for operating said guide from said pawl, as set forth.

3. The reciprocating guide G, slotted so as to be adjustable, in combination with the cross-head and its operating mechanism, substantially as set forth.

In testimony whereof I do affix my signature in presence of two witnesses.

JOSEPH S. SACKETT.
